UNITED STATES PATENT OFFICE.

HENRI A. ERNST, OF CHICAGO, ILLINOIS, ASSIGNOR TO ROBERTS AND SCHAEFER COMPANY, OF CHICAGO, ILLINOIS, A CORPORATION OF ILLINOIS.

COAL CHUTE AND APRON.

Application filed May 17, 1922. Serial No. 561,702.

To all whom it may concern:

Be it known that I, HENRI A. ERNST, a citizen of Canada, residing at Chicago, in the county of Cook and State of Illinois, have 5 invented a certain new and useful Improvement in Coal Chutes and Aprons, of which the following is a specification.

My invention relates to improvements in radially movable chutes or sway aprons and 10 means for operating them, for use in connection with storage and supply bins, elevators and the like. It has for its object to provide improvements in the mechanism for controlling the discharge of the contents of such 15 bin, and particularly relates to improved means for controlling the radial apron, chute or feeding means which delivers material discharged from such bin. A particular object is to provide a sway apron or chute 20 which may be swiveled and which may be used in combination with an undercut gate. Other objects will appear from time to time in the course of the specification.

I illustrate my invention more or less diagrammatically in the accompanying drawings, wherein—

Figure 1 is a vertical section;

Figure 2 is a front elevation;

Figure 3 is a partial plan view of the 30 lower part of Fig. 1; and

Figure 4 is a perspective view with parts omitted.

Throughout the specification and drawings the same parts are indicated by the same 35 characters.

A is the wall of any suitable bin or storage member, the lower and preferably inclined wall or floor B of which is adapted to direct material therein contained to the delivery 40 spout C, which preferably projects a substantial distance through and beyond the wall A. Pivoted, as at D, to the sides of the spout are the side elements D¹ of the undercut gate, the forward portion D² of 45 which is adapted to close the spout C. The side walls of the spout terminate in arcuate edges to make a snug fit with the arcuate member D².

Secured to the members D¹ are the bars 50 F, F¹, of which F¹ is vertical throughout substantially its entire length, the bar F having an upper horizontal section F² which crosses over and connects to the upper portion of F¹, the whole structure being braced as

by the brace element F³. Pivoted to the 55 outwardly inclined top section F⁴ of F¹ is the operating rod G, which is preferably joined to it by any suitable universal connection G¹. The rod G is provided with a handle G² and a chain G³, which is secured 60 to the outer end of the radially pivoted chute later to be described.

Secured to F¹ is a cord H, which is carried around the sheave H¹ and pulley H² mounted on the frame of the bin and has a 65 depending portion H³ to which are secured the weights H⁴, which normally tend to hold the undercut gate in closed position.

I, I¹ are brackets secured to and outwardly projecting from the frame of the bin, one 70 above and the other below the spout C, and lying in a vertical plane about midway between the sides of the spout. Pivoted in any suitable way to these brackets is a frame comprising side elements I², the bottom element I³, the cross-bars I⁴, the inclined top elements I⁵ and the horizontal top elements I⁶, I⁷ which connect them, and which are pivotally secured to the bracket I. Pivoted in any suitable manner to the side elements I², 80 as at K, K, is any suitable sway apron or chute K¹, the inner edge K² of which lies substantially beneath and within the end of the chute C. Secured to the outer end of the apron is the yoke L, to which is fastened 85 the cord M, which is brought about the sheave M¹ on the bin frame and is secured, as at M², to the bin. The weights M³ tend to lift the rope M from the yoke L into operative position, or the weights will be balanced merely to permit easy manipulation.

It will be realized that while I have illustrated and described an operative device, still many changes might be made in the number, size, shape and relation of parts 95 without departing from the spirit of my invention. I wish, therefore, that my drawings be considered as in a sense diagrammatic.

The use and operation of my invention 100 are as follows:

I have illustrated a form of chute and sway apron with which an undercut gate may be used. For this purpose I employ a bin having an outwardly projecting feed 105 or discharge spout, the end of which is closed by a radial gate which, when open, is rotated to a position beneath the end of

the spout. To insure a snug fit, the side walls of the spout terminate in arcuate edges co-axial with the gate. The gate is provided with a rod, to which is secured a rope which is carried about sheaves or pulleys and provided with weights which tend to close the gate. The weights may be so balanced that the gate holds any position in which it is manually placed, thus insuring easy manipulation. The discharge spout and gate project through a frame, which is pivoted above and below it to the supporting storage or bin framework. This frame rotates about a vertical axis and to its side members is pivoted a sway apron or chute, the pivotal connection of which with the frame makes virtually a universal joint. The chute is entirely out of connection or contact with the discharge spout and there is sufficient room between chute and spout for the radial gate to be withdrawn, thus permitting the use of an undercut gate, which is highly advantageous—for example, in coal work, since an overcut gate is easily jammed and, if struck with a flat piece of slate, as frequently happens in practice, may permit the spilling of fifty or one hundred tons on a locomotive. Like the gate, the chute is supported by a weighted cable, which either tends to lift it or so balances it as to make manual manipulation easy. The adjustment of the chute is entirely independent of the position of the gate and may freely be raised or lowered or rotated about a vertical axis. The result is an extremely flexible and efficient type of feed chute, which is coupled with a high

degree of control of the stream of material delivered to it by the spout.

I claim:

1. The combination with a storage bin having a downwardly and outwardly inclined spout of an under-cut gate pivoted upon the end of said spout and adapted, when open, to swing downwardly therebeneath, a chute supporting element pivoted adjacent said spout on a vertical axis, and a chute pivoted thereupon on a horizontal axis, the distance between the chute and the bottom of the spout being sufficient to provide clearance for the undercut gate as it swings into open position.

2. The combination with a storage bin having a downwardly and outwardly inclined spout of an under-cut gate pivoted upon the end of the spout and adapted, when open, to swing downwardly therebeneath, a chute supporting frame surrounding said spout pivoted on a vertical axis at top and bottom, a chute pivoted upon said frame at the sides thereof, the distance between the chute and the bottom of the spout being sufficient to provide clearance for the under-cut gate as it swings into open position, the distance between the sides of the frame and the sides of the spout being sufficient to permit rotation of frame and chute about a vertical axis.

Signed at Chicago, county of Cook and State of Illinois, this fourth day of May, 1922.

HENRI A. ERNST.
